UNITED STATES PATENT OFFICE.

AUDLEY D. MAXWELL, OF BYROMVILLE, GEORGIA.

GAME-BOARD.

1,145,783.

Specification of Letters Patent.

Patented July 6, 1915.

Application filed November 24, 1913, Serial No. 802,759. Renewed November 20, 1914. Serial No. 873,241.

To all whom it may concern:

Be it known that I, AUDLEY D. MAXWELL, a citizen of the United States, residing at Byromville, in the county of Dooly and State of Georgia, have invented certain new and useful Improvements in Game-Boards, and hereby declare that the following is a full, clear, and exact description thereof, reference being had to the accompanying drawings, which form part of this specification.

This invention is a novel game for the amusement of young persons and interesting to elders. The game is primarily intended for the amusement of boy scouts and boys who might not be quite old enough to join the organization, and the game board may be attractively ornamented by panoramic views of scenes and incidents in a boy scout's life, as such.

The game in brief comprises a set of movable pieces, and a board which may have a number of starting points, one for each player; and a preferably centrally located objective point. From each starting point the pieces are to be moved along certain lines past various "stops" en route; the path of the pieces toward the objective point being determined by the use of distinctive lines, and the movements of the pieces being controllable by some indicating device, such as a rotatable disk or pointer, which is operated by each player in turn; and such player moves his piece or pieces according to the color or designation shown by the indicator, and according to the rules hereinafter explained. The board is so arranged that the route of each piece from its starting point to the objective point, and return to starting point is desired, will be devious and undeterminable in advance.

In the accompanying drawing I have conventionally illustrated one form of game apparatus embodying the invention, and will briefly explain same, and then state more generally the incidental features of the game which enhance its attractiveness, but are not essentials of the invention.

Referring to said drawing; the game apparatus comprises a board of any suitable size and kind, upon which may be printed or lithographed, preferably in colors, the

starting points, routes, stops, and objective point. As shown this board has four starting points, indicated at A, B, C, D, (preferably arranged one at each side); and a central objective point indicated at E.

Each starting point has a plurality of spots or circles, four being shown indicated at 1, 2, 3, 4, which are preferably distinctively marked,—as by different colors; red, blue, green, and yellow, being indicated in the drawings. From each of such spots leads a similarly distinctive line 1^a, 2^a, 3^a, 4^a, which lines preferably extend to various different "stops" indicated by circles. A number of these stops 5 are located at different points on the surface of the board, and various different distinctive lines lead from one stop to another, until they eventually reach the innermost stops 1^b, 2^b, 3^b, 4^b, from each of which a single distinctive line passes to the objective point E. The number and arrangement of the stops 5 is entirely optional with the maker of the game board; but there should be enough "stops" to make the passage of the pieces from their starting points to the objective point devious and uncertain. The objective point may be called "home" if desired to end the game at that point; or the pieces can be returned from the objective point to the original, or some other designated starting point as "home" to prolong the game.

Each player is preferably provided with a plurality of pieces or "men", four being indicated at a, b, c, d; which may be distinctively marked or colored so that each player will know his men.

In the inner space may be placed a rotatable indicator F, which can be spun by hand, and which is surrounded by a circle f having its various segments distinctively marked or colored to correspond with the markings of the starting points 1, 2, 3, 4, and the lines leading therefrom. Each player should operate the indicator and move his men according to the marking or color at which the indicator stops. Obviously the indicator might be separate from the board.

The entire board or stops thereon may be illustrated with scenes representing camp life, hunting, chases, rowing, racing, &c. These illustrations need not necessarily be

on the stops from one move to another, but may be scattered indiscriminately over the entire board.

- To illustrate, a piece moving from a starting point would rest on one of the stops, from which there would lead one or more lines of different colors. The indicator might next show blue; if there were no blue line leading from such stop, the piece would remain. If there was a blue line it could be moved thereover to another stop. The game can be played by two or more players up to four, but four is preferable. The rules will provide a penalty for failing to send an opponent's man back two spaces when the opportunity comes or such man is overtaken and other incidents of the game as it progresses. The player who first gets all of his men "home" wins the game.
- 20 The game may be played as follows: The four players each select four men, and place them on the four spots immediately in front of their respective starting points. The first player will spin the indicator and the color on which the indicator stops will show the man to move off, following the same colored line and moving to the right.
- 25

If the indicator stops immediately in front of a red segment, the player will be allowed to advance either of his men along a red line. If there is no red line projecting from either of the stops his piece occupies, he can make no move; and the go passes to the next player. If the throw is successful, the man will move his piece as indicated, and will have one more go and then stop and the next player will have a go. If any player's piece overtakes an opponent's, the latter may be sent back to stops. A piece sent home must move out on the same colored line on which it enters.

The pieces or "men" are preferably made solid color on one side and checked on the other to show whether a man is just starting or nearing "home." By having the men a solid color on one side and checked on the other it can be determined whether a man is just starting or nearing home and after reaching the objective point or after passing an imaginary or visible line from the center of the board to the corner on the player's left and next the player, the man could be turned over and this would indicate that the man was nearing home.

55 The cardinal rules are that each piece moves only along the lines indicated by the disk pointer after same is spun, and that no backward moves are permitted.

60 The actual board could be made to represent various scenes, games, recreations, and incidents generally encountered in the life of a boy scout; marching, hunting, rowing, camping, etc. The corners, for instance, will represent a pitched camp, a game of ball, a canoe river trip, and a drill ground.

Some of the lines from one stop to another may be along a country road, a stream, a wooded pathway, a hare and hound race, a foot race and the like. Other lines will be plain.

70 Although I have described and prefer to have the starting points and lines of various colors as explained, it is obvious that instead of colors lines of different characteristic appearance might be used, such as indicated in the drawing, and these I consider the full legal equivalent of colored lines.

75 By having the home the original starting point, it will be observed that a man appearing before this "home" could enter only on the line as indicated by the disk, and if the home was in the center with only one line entering, a man would necessarily go in on any throw and would probably have a short cut. The four circles placed on each side of the center square are to make a better distribution over the board and possibly lead a man over an out of the way route.

80 What I claim is:

1. A game apparatus having a plurality 90 of starting points, an objective point and intermediate stops, differently colored lines leading from the starting point to different stops, a plurality of differently colored lines leading from each stop to others, and movable pieces for each player adapted to be moved from the starting point by the stops to the objective point.

95 2. A game apparatus having a plurality of starting points, an objective point and intermediate stops, distinctively-colored lines leading from each starting point to the different stops, and a plurality of such colored lines leading from each stop to others, and movable pieces for each player adapted 100 to be moved from the starting point by the stops to the objective point; and changeable indicating device whereby the movement of the pieces on the board is determined.

105 3. A game apparatus having a plurality of starting points, an objective point and intermediate stops, distinctively-colored lines leading from each starting point to the different stops, and a plurality of such lines leading from each stop to others; and pictorial representations of scenes along the route of the pieces; with a set of movable pieces for each player adapted to be moved 110 from the starting point by the stops to the objective point.

115 120 4. A game apparatus having a plurality of starting points, an objective point and intermediate stops, distinctively-colored lines leading from each starting point to the different stops, a plurality of such lines leading from each stop to others; and pictorial representations of scenes along the route of the pieces intermediate the starting points; with a distinctively-marked changeable indicating device whereby the movement of 125 130

the pieces on the board is determined; and distinctively-marked sets of movable pieces adapted to be moved by the players from the starting point along the lines, substantially as described.

5. A game apparatus having a plurality of starting points, an objective point and intermediate stops, and a plurality of distinctive lines leading from the starting 10 points to the different stops, and a plurality of distinctive lines leading from each stop to others, and from some stops to the objective

point; and movable pieces adapted to be moved along the lines from the starting point to successive stops and to the objective 15 point.

In testimony that I claim the foregoing as my own, I affix my signature in presence of two witnesses.

AUDLEY D. MAXWELL.
